**GOVERNING MECHANISM FOR EXTRACTION
TYPE STEAM TURBINE**

Jack M. Baker, Schenectady, N. Y., assignor to General Electric Company, a corporation of New York

Application August 17, 1956, Serial No. 604,688

9 Claims. (Cl. 60—67)

This invention relates to governing mechanism for an elastic fluid turbine, specifically a steam turbine of the "extraction" type, having an inlet valve controlling the admission of steam to a first high pressure turbine section in series flow relation with one or more lower pressure turbine sections, some of which have a valve for regulating the pressure of steam extracted from the turbine by altering the flow of motive fluid to successive lower pressure sections of the turbine. This invention is a further improvement on the so-called "three-arm" type of extraction governor disclosed in U. S. Patent 2,111,420, issued March 15, 1938, on an application of F. R. Ericson and E. D. Dickinson.

In recent years the extraction type steam turbine has become popular for application in industrial plants such as paper mills or chemical factories where substantial quantities of electric power are consumed and there is great need for steam at various pressures for heating and other process purposes. Such an industrial plant can often generate its own electrical energy at less cost than purchasing it from a public utility; and process steam at various pressures may be conveniently obtained by employing an extraction turbine having an appropriate number of sections with "controlled extraction" conduits having valves actuated by pressure governors for keeping constant at desired values the pressure of the steam extracted from the various sections. In some of such plants, it has been found desirable to use extracted steam in heat exchangers for raising the temperature of the water going into the boiler. This may be accomplished efficiently by extracting the feedwater heating steam from a low pressure section of the turbine. Since, in plants having a boiler supplying a single turbine, the steam requirements of the feedwater heater will bear a definite relation to the total flow of steam entering the turbine, it has been found possible, by means of the improvement in the three-arm governing mechanism described herein, to avoid the need for a pressure governor and extraction valve for controlling the pressure of the steam delivered to the feedwater heater. A special problem arises from the fact that the mechanical power output of the turbine, used to drive the generator for supplying the electrical needs of the plant, must be maintained essentially constant at a desired value, unaffected by the variable requirements of steam taken through the "controlled" extraction conduits (i. e. those in which the pressure is controlled by a pressure governor) and the "uncontrolled" extraction conduit (having no pressure governing device) supplying the feedwater heater.

Accordingly, an object of this invention is to provide an improved form of extraction turbine governor capable of maintaining constant the mechanical power output of the turbine irrespective of variable extraction of steam from a turbine section having no pressure governor for regulating the pressure of the extracted steam.

A further object is to provide an improved extraction governor of the type described particularly adapted for supplying steam to a feedwater heater without the addi-

2

tional complexity of a pressure governor and extraction valve for controlling the pressure of such feedwater heating steam.

Other objects and advantages will become apparent from the following description taken in connection with the accompanying drawings in which:

Fig. 1 is an improved three-arm extraction governor incorporating the invention in its simplest form as applied to a turbine having only two sections; Fig. 1a is a diagrammatic illustration of the method of operation of the three-arm governor of Fig. 1; and

Fig. 2 represents the application of the invention to a turbine having three sections with two "controlled" extraction openings (each having a separate pressure regulator) and one "uncontrolled" opening (having no pressure regulator).

Generally stated, the invention is practiced by providing the three-arm governing mechanism with modifying linkage means which positions the three-arm lever in the same manner as the speed governor, the increment of motion produced by this linkage being a function of changes in pressure in the turbine section immediately upstream from that from which the uncontrolled extraction is taken.

Referring now more particularly to Fig. 1, the invention is illustrated as applied to a steam turbine plant comprising a two-section turbine illustrated generally at 1, driving an electrical generator 2 and supplied with steam by a suitable boiler 3. The boiler supplies motive fluid by way of conduit 3a to the high pressure turbine section 1a, as controlled by inlet valve 1b. The second turbine section 1c is supplied with motive fluid at a variable rate by means of the extraction valve 1d. Process steam is extracted at a variable rate from the low pressure end of the first turbine section 1a by way of a "controlled extraction" conduit 4, at a rate determined by the requirements of the consumer 4a, represented for instance by the valve 4b, and at a constant pressure maintained by the pressure governing device 11, the action of which is described more particularly hereinafter. It is the presence of this pressure governor 11 which makes the conduit 4 a "controlled extraction conduit." Condensate exhausted from the consumer 4a is returned by conduit 5 to the feedwater heater 6, which is connected by conduit 6a with the boiler 3. There will usually be some loss of steam in the consumer 4a, so that the quantity of condensate returned through conduit 5 is not the same as that received through conduit 4. This inevitable loss is represented by the vent conduit 4c and the quantity of flow therethrough is represented by the valve 4d. It is to be noted that the quantity of this leakage is a function of the nature and operating condition of the consumer 4a, and that this leakage will ordinarily be substantially constant in plants of the type for which the invention is intended, so that the quantity of steam or condensate returned through conduit 5 will be a fairly definite known function of the steam received through conduit 4.

In accordance with the invention, the heat source for the feedwater heater 6 is steam extracted from the last turbine section 1c, as represented by the "uncontrolled extraction" conduit 6a communicating with the turbine section 1c at a location where the pressure is appropriate for the needs of the feedwater heater. It will be appreciated by those familiar with the art that the flow of steam through conduit 6a to the feedwater heater 6 is regulated by a suitable device (not shown) which may, for instance, be responsive to the temperature of the feedwater leaving the heater through conduit 6a. The precise means used to control the operation of the feedwater heater 6 is not a part of this invention, but is represented diagrammatically by the valve 6b. Thus it will be appre-

ciated that the "uncontrolled extraction" through conduit 6a is at a rate determined by the independent requirements of the feedwater heater, and not under the control of a pressure governing component of the "three-arm governing mechanism" described herein. This flow is not a constant function of the rate of steam flowing through the low pressure turbine section 1c; but is rather a function of the total flow of steam supplied to the turbine, which of course varies by reason of the variable requirements of the consumer 4a.

Thus it will be seen that the term "uncontrolled extraction," as used herein, means that the turbine governing system includes no pressure responsive regulating valve for determining the pressure of the steam extracted, i. e., the turbine governor has no control over the extraction steam but must act properly irrespective of the quantity of steam taken from the "uncontrolled" extraction stage. Thus, conduit 4 represents "controlled extraction" since it has an associated pressure governor 11, and conduit 6a represents "uncontrolled extraction," having no pressure governor incorporated as part of the turbine governing mechanism.

The steam exhausted from the low pressure turbine section 1c is received by condenser 7, whence the condensate is returned by boiler feed pump 8 through conduit 5a. It will be understood that the pump 8 is a diagrammatic representation of pump means for getting all the condensate back into the boiler. Actually, the conduit 5 could conceivably discharge into the condenser 7, depending on the temperature and pressure conditions at which the fluid is exhausted from the consumer 4a. It need only be noted here that suitable pump means is provided for returning the exhaust from the consumer 4a and the condensate from condenser 7 to the feed-water heater 6.

It will now be seen that the total flow of steam into the turbine is a joint function of the mechanical power required by the load generator 2, and of the process steam required by the consumer 4a, and of the demand for heating steam in the feedwater heater 6, which latter is in turn a function of the total steam flow from the boiler. This interrelation of variable factors results in a variable demand for steam in the feedwater heater, which necessitates a modification in the three-arm governing mechanism in order to avoid undesirable fluctuations in the mechanical power output available to the generator 2.

As described more completely in the above-mentioned Ericson et al. Patent 2,111,420, the basic three-arm governor comprises a T-shaped floating lever member, shown at 9 in Fig. 1 herein, interconnecting the speed governor, the extraction pressure governor, and the main inlet valve and extraction valve. The flyball speed governor 10 is driven at a speed proportional to the turbine rotor speed, and is connected to position the fulcrum pivot 9a of the three-arm lever 9 as a function of the mechanical power output required by the load generator 2. The extraction pressure governor 11 is responsive to the pressure of steam extracted through the "controlled extraction" conduit 4, by reason of the pressure-sensing conduit 11a, and has an output rod 11b connected by pivot 9b to one arm of the three-arm lever 9. Another arm is connected at pivot 9c to position the actuating rod of inlet valve 1b. The third arm is connected by pivot 9d to position the extraction valve 1d.

It will be understood by those acquainted with extraction governors of this type that the general operation is that the governor 10 moves the pivot point 9a up and down so that the valves 1b, 1d are moved in the same direction, that is, both valves open or both close, simultaneously to increase or decrease the steam flow through the turbine, as required by variations in the demand for mechanical power output, while the pressure governor 11 causes the three-arm lever 9 to rotate about the fulcrum 9a, moving valves 1b, 1d in opposite directions, one valve opening while the other closes, in order to control the pressure of the steam extracted through conduit 4. The

design of the linkage is such that the mechanical power output will remain constant as determined by the setting of the speed governor 10, while the extraction pressure in conduit 4 will remain constant as determined by the setting of the pressure governor 11. The speed setting of governor 10 is represented diagrammatically by a "synchronizing screw" 10a which carries the movable fulcrum 10b, the position of which determines the speed which will be held by the governor 10. Of course, appropriate means may be provided also for adjusting the pressure which will be held by the pressure governor 11. Such details do not form a part of the present invention and need not be described further here.

In accordance with the invention, the governor 10 is not connected directly to the three-arm fulcrum pivot 9a but has interposed therebetween a special modifying linkage indicated generally at 12. This linkage comprises a lever 12a having an intermediate pivot connected by link 12b to the fulcrum 9a, and a first end pivot connected by link 12c to the left-hand end of speed governor lever 10c. The other end of lever 12a is connected by link 12d to a bell-crank arm 12e, the other arm 12f of which is forked so as to straddle the pressure governor actuating rod 11b. A compression spring 13 biases the bell-crank arm 12f counterclockwise into engagement with a stop member represented by a transverse abutment pin 11c projecting from the rod 11b. The action of the spring 13 is to maintain arm 12f always in contact with the abutment 11c so that ordinarily the bell-crank 12e will behave precisely as if it were pivoted to follow the motion of the rod 11b. The purpose of this "breakaway connection" is to permit the modifying linkage to be disconnected by turning the "lockout screw" 14 so as to move bell-crank arm 12f to the right against the bias of spring 13, so as to remain out of contact with the abutment 11c. In ordinary operation, the lockout screw 14 will be backed off to the left, as shown in Fig. 1, so as to have no effect on the bell-crank, which will then follow the motion of the pressure governor rod 11b.

It will be seen from Fig. 1 that the effect of this modifying linkage 12 is to cause the three-arm fulcrum 9a to be positioned in a vertical path as a function of the action of the speed governor 10 and by an additional increment effected by the pressure governor 11.

The operation of the modified three-arm governor illustrated in Fig. 1 is as follows. Assume first that the boiler is supplying steam to the turbine without the feedwater heater 6 in operation, and with no steam being extracted through the conduit 4. For this condition the pressure governor rod 11b will be in a fixed position and the lockout screw 14 will be holding bell-crank 12f in a fixed position, away from abutment 11c. The speed governor 10 will now move the fulcrum point 9a vertically so as to position the inlet valve 1b and extraction valve 1d in the same direction by proportional amounts, since all the flow through the inlet valve 1b is also flowing through the extraction valve 1d into the low pressure turbine section 1c.

If now it is desired to extract steam for the consumer 4a, but with the feedwater heater 6 still inoperative, the lockout screw 14 will be maintained against the bell-crank arm 12f to hold it to the right, away from abutment 11c, so that the linkage 12 is disabled. Pressure governor 11 will now respond to the varying pressure in extraction conduit 4 in accordance with the varying demand of consumer 4a and cause the three-arm lever 9 to rotate about the fulcrum point 9a to position the inlet valve 1b and extraction valve 1d differentially (in opposite directions) so as to maintain constant the extraction pressure, as described more particularly in the above-mentioned patent to Ericson et al.—2,111,420.

Now assume that the valve 6b is opened to admit steam at varying rates as required by the feedwater heater 6. The pressure governor 11 will try to adjust the valves 1b, 1d so as to maintain constant the extraction pressure

in conduit 4. However, the variable "uncontrolled" extraction through conduit 6a means that a large demand for steam in the feedwater heater 6 will deprive the lower pressure stages of the second turbine section 1c of motive fluid, and therefore tend to result in inadequate mechanical power output. To compensate for this tendency, the lockout screw 14 is backed away from the bell-crank arm 12f so that it is free to follow the abutment 11c. The operation is now as follows.

Assume that, with the linkage in the condition shown in Fig. 1, the feedwater heater control valve 6b should open to admit more steam to the feedwater heater. Thus deprived of a portion of its motive fluid, the turbine rotor will tend to slow down, with the result that the flyweights of governor 10 move inwardly so that pivot point 10d rises. Link 10c pivots clockwise about the fixed right-hand end pivot 10b so that link 12c causes the left-hand end of lever 12a to rise, and link 12b moves the fulcrum pivot 9a vertically upward.

Referring to Fig. 1a, assume that this motion results in the three-arm lever 9 moving from the position indicated by the solid line A to the new broken line position identified B, which is essentially parallel to A. This has the effect of opening both inlet valve 1b and extraction valve 1d, by proportional amounts. Opening the inlet valve 1b of course has the effect of admitting more motive fluid so as to increase the power output of the high pressure turbine section 1a. This will tend to bring the rotor speed back to the normal value for which the governor synchronizing screw 10a is set. Opening movement of the extraction valve 1d will also increase the flow into the low pressure section 1c, as required by the increased feedwater heater demand. For an increase in demand for steam in the feedwater heater 6, and likewise for an increase in demand for mechanical power output, the control system responds to satisfy these demands, within normal "speed regulation" of the speed governor 10, while keeping constant the controlled extraction pressure in conduit 4. But now assume operation at line A and a constant demand for mechanical power output. Then an increase in the demand for steam in controlled extraction conduit 4 will decrease the pressure transmitted to the pressure governor 11, causing the spring 11d to move the bellows abutment 11e to the right, so that actuating rod 11b pulls on pivot 9b to rotate the three-arm lever clockwise about fulcrum pivot 9a. Thus, again referring to Fig. 1a, if operating with three-arm lever 9 in position A without the invention (with lockout screw 14 holding bell crank 12f in a fixed position away from abutment 11c), the three-arm lever would rotate about fulcrum 9a to position C. This would open the inlet valve 1b to increase steam flow to the turbine 1a, and would somewhat close extraction valve 1d to decrease steam flow to the low pressure turbine section 1c, so that the differential between steam flow to section 1a and that to section 1c is sufficient to satisfy the increased steam demands in the controlled extraction conduit 4. This decrease in steam flow to the low pressure turbine section 1c occurs at a time when an increased flow of steam is required to feedwater heater 6 (due to the increase in steam flow to section 1a). Furthermore, the total mechanical power output of the turbine sections 1a, 1c will drop due to the diversion of steam through conduit 6a. However, with the invention in operation (lockout screw 14 backed off to the left, permitting bell-crank 12f to follow abutment 11c), simultaneous with the increased flow of controlled extraction steam in conduit 4, the motion to the right of rod 11b causes abutment 11c to move bell-crank 12f, 12e clockwise so link 12d rises and pulls upwardly the right-hand end of lever 12a. The three-arm lever 9 now moves directly from position A in Fig. 1a to position D, with the increased controlled extraction demand in conduit 4 and the uncontrolled extraction demand in feedwater heater 6 both satisfied, and with the same mechanical power output as before. It is to be noted

that this change is effected with no change required in speed of the turbine or in position of the speed governor lever 10c. Thus the modifying linkage means 12 has the effect of causing link 12b to move upwardly by an increment such that the three-arm lever 9 assumes the position identified D in Fig. 1a, solely under the action of the pressure governor 11 and without change in the condition of speed governor 10.

Stated another way, the compensator 12 has the net effect of altering the ratio by which the inlet valve 1b is opened for a given opening motion of the extraction valve 1d. In Fig. 1a, it can be seen that the valve-opening movement of point 9c, in going from position A to position D (with the modifying linkage 12 in operation) is greater than its movement from position A to position B; while the opening movement of point 9d, in going from A to D, is less than its movement from A to B. This means that the operation illustrated in Fig. 1a could be achieved also by shifting the fulcrum pivot 9a towards the right-hand pivot 9d. With the fulcrum 9a so relocated, it will be apparent that rotation of the three-arm by the pressure governor 11 would cause a proportionately greater movement of inlet valve 1b than the corresponding motion produced on extraction valve 1d.

The extra increment of opening motion thus communicated to inlet valve 1b due to change in controlled extraction demand in conduit 4, supplies the additional motive fluid required to satisfy the increased extraction demand from the feedwater heater 6, while maintaining the extraction pressure in conduit 4 at the preset value, without reducing the mechanical power output to the generator 2 and without causing the speed of the turbine-generator to change. Thus by proper design of the linkage described above, the conventional three-arm type of governor can be made to keep the mechanical power output constant with changes in "controlled extraction" demand and irrespective of changes in the "uncontrolled extraction" from the low pressure section 1c to the feedwater heater 6.

Fig. 1 is only a very diagrammatic showing of one form of the invention. In an actual machine, the speed governor 10 would position the pilot valve of a hydraulic servo-motor which would in turn position the fulcrum pivot 9a. Likewise, the pivots 9c, 9d would be connected to position the pilot valves of servo-motors which would furnish the power required to position the steam valves 1b, 1d. Such details of the actual mechanism have been omitted for the sake of clarity.

Likewise, it will be seen from the above that the invention may be practiced by physically shifting the pivot 9a closer to the pivots 9c or 9d as the case may be, provided suitable extraction pressure responsive mechanism is provided to perform this function. The linkage shown in Fig. 1 is a simple and reliable mechanical expedient for obtaining the same result as would be obtained by shifting the pivot 9a.

The invention is applicable also to more complicated three-arm extraction governing systems, one of which is illustrated in Fig. 2. Here similar components are indicated by like reference numerals as used in Fig. 1.

Referring more particularly to Fig. 2, it will be seen that the inlet valve 1b has its valve stem pivoted at 15 to a floating lever 16, the right-hand end of which is connected to the three-arm pivot 9c. The left-hand end of lever 16 is pivoted at 16a to a bell-crank 17 the other arm of which is pivoted at 17a to the actuating rod 18a of the extraction pressure governor 18. This governor is responsive by way of conduit 19a to the extraction pressure in conduit 19 which communicates with the intermediate turbine section 1e. As with the governor of Fig. 1, the function of the three-arm lever 9 is to open and close the inlet valve 1b and the extraction valves 1d, 1f as a function of changes in load, while the extraction pressure governor 11 produces a differential movement 75 of the inlet valve 1b as compared with that of the ex-

traction valves $1d$, $1f$, by effecting rotation of the three-arm lever 9 about its fulcrum pivot $9a$. The addition of the intermediate turbine stage $1e$ requires a second three-arm lever shown at 20 . The left-hand arm of this lever is pivoted at $20a$ to the stem of extraction valve $1f$, and the right-hand end is pivoted at $20b$ to the stem of extraction valve $1d$. The third arm carries a roller member $20c$ which engages a recess in a guide block $20e$ carried on the actuating rod $18a$ of pressure governor 18 . The basic operation of a multiple three-arm governing system of this type will be seen from the above-mentioned Ericson et al. Patent 2,111,420.

In the governor of Fig. 2, the present invention is incorporated in the linkage which connects the right-hand pivot $9d$ of three-arm lever 9 with the common point or fulcrum pivot $20d$ of the second three-arm lever 20 . This compensator linkage, identified generally by the reference numeral 21 , comprises a link $21a$ pivoted at $9d$ to the first three-arm lever 9 and to an intermediate portion of a lever $21b$, the right-hand end of which is carried on a fixed fulcrum $21c$. The left-hand end is pivoted at $21d$ to a link $21e$ which is in turn pivoted at $21f$ to the left-hand end of a second lever $21g$. Link $21h$ is pivoted at $21i$ to lever $21g$, and carries at its lower end the common fulcrum $20d$. The right-hand end of lever $21g$ is connected by a link $21j$ to a bell-crank $21k$ the other arm of which is pivoted at $21m$ to the pressure governor actuating rod $18a$. The general similarity of the compensator linkage 21 to the linkage 12 in Fig. 1 will be apparent.

The operation of a multiple three-arm governing system becomes extremely complex as the number of turbine sections increases beyond 2, because of the many inter-related factors; and it is believed unnecessary to describe in complete detail the operation of the multiple three-arm mechanism shown in Fig. 2. The basic operation is as described in Patent 2,111,420; and the compensator mechanism 21 operates in the same manner as the linkage 12 in Fig. 1. However, by comparison of the structures of Figs. 1 and 2 herein, the following points of similarity will be observed. In each case, the modifying linkage is incorporated in the mechanism which positions vertically the fulcrum pivot of the three-arm lever controlling the two steam valves immediately upstream from the turbine section having the "uncontrolled" extraction (that is, valves $1f$ and $1d$ in Fig. 2 and valves $1d$ and $1b$ in Fig. 1). The modifying effect is produced in accordance with changes in the pressure of the "controlled" extraction stage immediately upstream from the "uncontrolled" extraction stage. The end result of the modifying effect is that the effective lever ratio of the three-arm is modified so as to produce increased movement of the higher pressure valve means for a given change in position of the lower pressure valve.

While only a limited number of embodiments of the invention are described herein, it will be apparent to those skilled in the art that many other variants are possible. For instance, if in the arrangement of Fig. 2 there were another feedwater heater supplied with heating fluid from the intermediate turbine stage $1e$, then a second modifying linkage in accordance with that shown at 12 in Fig. 1 could be substituted for the link $12b$ which in Fig. 2 connects the pivot point $10d$ of the flyball governor with the fulcrum point $9a$ of the first three-arm lever. In other words, it is necessary to provide this modifying means in the action of each three-arm lever which controls the two valves immediately upstream from the section of the turbine from which an "uncontrolled" extraction conduit takes fluid.

While the primary application for the invention described herein has been for steam turbine plants where the uncontrolled extraction steam is used in a feedwater heater, the invention may also be applied to extraction turbines where the uncontrolled extraction is used for other heating purposes, such as another chemical process

analogous to that represented by $4a$, where the exhaust steam from this consumer is returned eventually as condensate to the boiler. The feedwater heater 6 may be either an "open" type, in which the steam accomplishes its heating function by merely being mixed with the condensate, or a "closed" type in which the condensate being heated passes through tubes and the heating steam flows over the outside of the tubes, with the result that the heating steam is eventually condensed and returned to the boiler with the other condensate. The principles of the invention are also applicable to extraction turbine governors of other types, such as those having hydraulic or other power actuated components equivalent to the mechanical linkage means disclosed herein.

- 15 It will be seen that the invention provides simple and effective means for modifying the action of the basic three-arm governor so as to render it applicable to extraction turbines having one or more uncontrolled extraction conduits supplying feedwater heaters.
- 20 It is, of course, desired to cover by the appended claims all such modifications as fall within the true spirit and scope of the invention.

What I claim as new and desire to secure by Letters Patent in the United States is:

- 25 1. In a governing system for a multiple section elastic fluid turbine having an inlet valve admitting motive fluid to a higher pressure turbine section and at least one extraction valve admitting motive fluid to a lower pressure turbine section from said higher pressure section, first conduit means extracting elastic fluid from said higher pressure section upstream from said extraction valve at variable rates, with automatic power means positioning said valves both in the closing direction or both in the opening direction as a function of turbine speed and positioning 30 one of said valves in the closing direction and the other in the opening direction as a function of changes in extraction pressure in said first conduit, the combination of a second extraction conduit supplying elastic fluid to a consumer at variable rates from said lower pressure turbine section downstream from said extraction valve, and means modifying the action of said automatic power means to move the inlet valve and the extraction valve both in the closing direction or both in the opening direction by increments which are a function of changes of pressure in said 35 first extraction conduit to hold substantially constant the mechanical power output of the turbine irrespective of variations in the amount of elastic fluid extracted from said first and second conduits.
- 40 2. In a governing system for a multiple section elastic fluid turbine having an inlet valve admitting motive fluid to a first high pressure turbine section and at least one extraction valve admitting motive fluid to a second lower pressure turbine section in series with said first section, a controlled extraction conduit extracting fluid at variable 45 rates from the first turbine section upstream from said extraction valve, with automatic servo means connected to position said valves in the same direction as a function of turbine speed and in opposite directions as a function of changes in pressure in the controlled extraction conduit, the combination of an uncontrolled extraction conduit supplying fluid at variable rates to a consumer from a location in the second turbine section downstream from said extraction valve, and means modifying the action of said servo means to cause said valves both to move in the 50 opening direction by an increment independent of any change in turbine speed and proportional to a decrease in pressure in said controlled extraction conduit to hold substantially constant the mechanical power output of the turbine regardless of variations in the amount of controlled 55 and uncontrolled extraction.
- 60 3. In a governing system for a multiple section elastic fluid turbine having an inlet valve admitting motive fluid to a first high pressure turbine section and an extraction valve admitting motive fluid to a second lower pressure turbine section from said first section, with controlled 65 increments which are a function of changes of pressure in the controlled extraction conduit to hold substantially constant the mechanical power output of the turbine irrespective of variations in the amount of controlled and uncontrolled extraction.
- 70 4. In a governing system for a multiple section elastic fluid turbine having an inlet valve admitting motive fluid to a first high pressure turbine section and an extraction valve admitting motive fluid to a second lower pressure turbine section from said first section, with controlled 75 increments which are a function of changes of pressure in the controlled extraction conduit to hold substantially constant the mechanical power output of the turbine irrespective of variations in the amount of controlled and uncontrolled extraction.

extraction conduit means removing elastic fluid from the first section at a location upstream from said extraction valve at variable rates and servo means connected to position said valves in the same direction as a function of turbine speed and in opposite directions as a function of changes in pressure in said controlled extraction conduit, the combination of an uncontrolled extraction conduit supplying elastic fluid to a consumer at variable rates from said second turbine section downstream from said extraction valve, and means positioning said valves both in the opening direction by increments proportional to decrease in said controlled extraction conduit pressure resulting from changes in the amount of fluid withdrawn through said controlled and uncontrolled extraction conduits to hold substantially constant the mechanical power output of the turbine regardless of variations in said fluid extraction.

4. In a governing system for a multiple section elastic fluid turbine having an inlet valve admitting motive fluid to a first high pressure turbine section and an extraction valve admitting motive fluid to a second lower pressure turbine section from said first section, with controlled extraction conduit means removing elastic fluid from the first section upstream from said extraction valve at variable rates and means connected to position said valves in the same direction as a function of turbine speed and in opposite directions as a function of changes in pressure in said controlled extraction conduit, the combination of an uncontrolled extraction conduit supplying elastic fluid at variable rates to a consumer from said second turbine section downstream from said extraction valve, and means for increasing the rate of opening movement of the inlet valve relative to the rate of opening of the extraction valve as a function of decreasing pressure in said controlled extraction conduit to hold substantially constant the mechanical power output of the turbine irrespective of variations in fluid extraction.

5. In a three-arm lever type governing system for a multiple section elastic fluid turbine having an inlet valve admitting motive fluid to a high pressure turbine section and an extraction valve admitting motive fluid from the high pressure section to a lower pressure section, with controlled extraction conduit means removing elastic fluid at variable rates from the first section at a location upstream from said extraction valve and three-arm lever means having a fulcrum pivot connected to speed-responsive means to position said valves in the same direction as a function of turbine speed and pressure responsive means connected to cause said lever to position said valves in opposite directions as a function of changes in pressure in the controlled extraction conduit, the combination of an uncontrolled extraction conduit supplying elastic fluid at variable rates to a consumer from the second turbine section downstream from said extraction valve, and servo means responsive to pressure changes in the controlled extraction conduit for moving said fulcrum pivot of the three-arm lever in the valve-opening direction as a function of decreasing controlled extraction pressure to increase the rate of opening movement of the inlet valve relative to opening movement of the extraction valve to hold substantially constant the mechanical power output of the turbine irrespective of variations in fluid extraction.

6. In a three-arm lever type governing system for a multiple section elastic fluid turbine having an inlet valve admitting motive fluid to a first high pressure turbine section and an extraction valve admitting motive fluid to a second lower pressure turbine section, with controlled extraction conduit means removing fluid at variable rates from the first section upstream from said extraction valve and a three-arm lever with a fulcrum pivot connected to speed-responsive means to position said valves in the same direction as a function of turbine speed and pressure-responsive means connected to cause said lever to position said valves in opposite directions

as a function of changes in pressure in said controlled extraction conduit, the combination of an uncontrolled extraction conduit supplying elastic fluid at variable rates to a consumer from said second turbine section downstream from said extraction valve, and means responsive to pressure in said controlled extraction conduit for moving the fulcrum pivot of the three-arm lever in the valve-opening direction by an increment proportional to decrease in controlled extraction pressure to increase the rate of opening of the inlet valve relative to the rate of opening of the extraction valve as a function of decreasing pressure in the controlled extraction conduit in order that mechanical power output of the turbine will remain substantially constant irrespective of variations in fluid extraction from said controlled and uncontrolled extraction conduits.

7. In a three-arm lever type extraction governing system for a multiple section elastic fluid turbine having an inlet valve controlling the admission of motive fluid to a first high pressure turbine section and an extraction valve admitting motive fluid from the first turbine section to a second lower pressure turbine section, with a controlled extraction conduit connected to remove elastic fluid at variable rates from the first turbine section at a location upstream from said extraction valve, and a three-arm lever with turbine speed-responsive means connected by first linkage means to a fulcrum pivot of the lever for positioning the fulcrum as a function of turbine speed and one arm connected to position the inlet valve, another arm connected to position the extraction valve, and pressure-responsive servo means connected to the third arm for rotating the three-arm lever about said fulcrum pivot in accordance with pressure changes in said controlled extraction conduit, said speed-responsive and pressure-responsive means acting on the three-arm lever to position both of said valves in the same direction as a function of rotor speed and in opposite directions as a function of controlled extraction conduit pressure, the combination of an uncontrolled extraction conduit supplying fluid at variable rates to a consumer from said second turbine section downstream from said extraction valve, and second linkage means connected to move in response to pressure changes in said controlled extraction conduit and connected to modify the action of said first linkage means to position the fulcrum pivot of the three-arm lever in the valve-opening direction by an increment proportional to decrease in controlled extraction pressure to increase the rate of opening of the inlet valve relative to the rate of opening of the extraction valve as a function of decreasing controlled extraction pressure.

8. In a governing system for a multiple section elastic fluid turbine having an inlet valve admitting motive fluid to a first high pressure turbine section and an extraction valve admitting motive fluid from said first section to a second lower pressure turbine section, with first extraction conduit means removing elastic fluid at variable rates from the first section upstream from said extraction valve, the combination of a three-arm lever member connected to position the inlet and extraction valves in the same direction as a function of translational movement of the lever and in opposite directions as a function of pivotal movement of the lever about a fulcrum, means responsive to turbine speed for effecting translational movement of the lever to open and close the valves together, means responsive to pressure in said first extraction conduit for effecting pivotal movement of the lever about said fulcrum to position the valves in opposite directions, and linkage means for effecting an additional increment of translational movement of the lever to increase the rate of opening movement of the inlet valve relative to the opening of the extraction valve as a function of decreasing pressure in said first conduit to hold substantially constant the mechanical power output of the turbine irrespective of changes in extraction flow.

9. In a governing system for a multiple section elastic fluid turbine having a first inlet valve admitting motive fluid to a first high pressure turbine section, a second valve admitting motive fluid from the first turbine section to a second intermediate pressure turbine section, a third valve admitting motive fluid from the second turbine section to a third low pressure turbine section, a first extraction conduit connected to supply fluid to a consumer at variable rates from the first turbine section at a location upstream from said second valve, a second extraction conduit connected to remove elastic fluid at variable rates from the second turbine section upstream from said third valve, a first three-arm lever member with a fulcrum connected to be positioned by a turbine speed-responsive device and having one arm connected to position said first valve, another arm connected to first pressure-responsive means to rotate said first lever about said fulcrum in accordance with changes of pressure in the first extraction conduit, and a third arm connected by first linkage means to the fulcrum pivot of a second three-arm lever having one arm connected to position the second valve and another arm connected to position the third valve, and second pressure-

responsive means connected to position the third arm of the second lever as a function of changes of pressure in the second extraction conduit, said speed-responsive device positioning the fulcrum of said first three-arm lever as a function of turbine speed to cause all three valves to move in the same direction as a function of turbine speed, the combination of a third extraction conduit connected to remove elastic fluid at variable rates from the third turbine section downstream from said third valve, and means responsive to pressure changes in said second extraction conduit for modifying the action of said first linkage means to move the fulcrum of said second three-arm lever in the valve-opening direction in accordance with a decrease in pressure in said second extraction conduit.
